CLAIM

(63) Continuation-in-part of application No.
PCT/US2013/042313, filed on May 22, 2013, which
(Continued)

An ornamental design for a mattress, substantially as shown.

(51) **LOC (10) Cl.** **06-09**

DESCRIPTION

(52) **U.S. Cl.**

FIG. 1 is a top, foot end, perspective view of a mattress
according to my new design;

USPC **D6/605**

FIG. 2 is a top plan view of the mattress of FIG. 1;

(58) **Field of Classification Search**

FIG. 3 is a bottom plan view of the mattress of FIG. 1;

USPC D6/595-601, 604-606; D21/803, 804,

FIG. 4 is a right side elevation view of the mattress of FIG.
1;

D21/809; D24/183; D30/118, 119

FIG. 5 is a left side elevation view of the mattress of FIG.
1;

CPC A47C 20/00; A47C 20/021; A47C 20/026;

FIG. 6 is a head end elevation view of the mattress of FIG.
1; and,

A47C 20/027; A47C 20/048; A47C

(Continued)

FIG. 7 is a foot end elevation view of the mattress of FIG. 1.

1 Claim, 6 Drawing Sheets

Related U.S. Application Data

is a continuation-in-part of application No. PCT/US2014/018033, filed on Feb. 24, 2014.
